UNITED STATES PATENT OFFICE

SOLOMON KENDRICK, OF ROCHESTER, NEW YORK, ASSIGNOR OF ONE-FOURTH TO EDWARD G. PFAHL AND ONE-FOURTH TO ALBRECHT VOGT, OF ROCHESTER, NEW YORK.

LOOM ATTACHMENT.

No. 919,023.

Specification of Letters Patent.

Patented April 20, 1909.

Application filed December 26, 1907. Serial No. 408,105.

To all whom it may concern:

Be it known that I, SOLOMON KENDRICK, a citizen of the United States, residing at Rochester, in the county of Monroe and State 5 of New York, have invented certain new and useful Improvements in Loom Attachments; and I do hereby declare the following to be a full, clear, and exact description of the invention, such as will enable others skilled in 10 the art to which it appertains to make and use the same.

This invention relates to improvements in attachments for looms, and is especially designed for use in connection with looms for 15 weaving silk and cotton elastic and non-elastic narrow fabrics.

One of the primary objects of the invention is to provide certain improvements in connection with the mounting and operation 20 of the reeds coöperating with the shuttle mechanism and the woven portion of the fabric to allow ample time for the shuttle to travel home in passing through the shed, and also to effectively engage and set the weft 25 threads, the whole coöperating to produce a loom for the manufacture of narrow fabrics capable of greater production of a better article than heretofore.

The particular features of novelty are 30 pointed out in the appended claims, and while the invention is not restricted to the exact details shown and described, still for the purpose of disclosure reference is had to the accompanying drawings illustrating a practical embodiment of the invention, in 35 which like characters designate the same parts in the several views, and in which—

Figure 1 is a perspective view of a narrow fabric loom with the invention applied thereto; and with some parts broken away for 40 clearness of illustration. Fig. 2 is a side elevation of same, and Fig. 3 is a detail view of the slotted finger coöperating with a temporary locking means for its particular reed.

45 1 designates the main frame, 2 and 3 the warp and cloth beams or rollers, 4 and 5 designating guide rollers for the woven fabric, 6 the driving belt, and 7 and 8 the fixed and loose driving wheels, all of which are of any 50 suitable construction.

9 designates a shipper, and 10 mechanism

forming a part of automatic means coöperating with said shipper 9 to provide an emergency stop motion, the details of which form no part of the present invention, and which 55 are specifically shown and described in my former patent, No. 871,704, patented Nov. 19, 1907.

While the particular form of bobbin cone and shuttle arrangement have certain decided 60 advantages, being for a separate invention, they form no particular part of the present invention and have only been illustrated broadly, and will only be referred to briefly.

11 designates a shuttle race affixed to the 65 loom frame in front of the several harness, and provided between the blocks 12 with openings forming a space to allow the reeds to pass back and forth.

The shuttles are designated at 13, and are 70 of oblong shape, tapering to the front. The inside face of the shuttle is oval and of sufficient depth to cover the base diameter of the cones 14, constituting the bobbins of filling material, the shape of the shuttle protecting the cone of material from engaging the warp threads. No particular means is 75 shown for imparting movement to the shuttles, it being understood that this may be done in the usual way. 80

15 designates the batten which is suitably mounted on the upper member 16 of a swinging frame formed by pivotally supporting the member 16 on the vertical bars 17 pivotally supported at their base. The upper 85 member 16 is connected to a pitman 18, pivoted at one end thereto, as at 19, and at its other end pivoted to a crank arm 20 on the loose driving wheel.

Referring to the particular features of 90 novelty in the present invention, 21 designates guide blocks mounted on the batten and coöperating with the reeds to form a guideway therefor.

The reeds consist of the ordinary form of 95 vertical members 22, but are provided at their base with horizontal extensions 23 slidably mounted, transversely of the batten 15, in relation to the blocks 21. The connections between the blocks and the base 100 member 23 may be any suitable form of sliding connection, such as tongue and

groove, and in the drawings the blocks are shown as being provided with tongues 24 operating in longitudinal side slots 25 in the reed base. The forward end of the reed base 23 is also slotted vertically, as at 26, and within said slot is suitably mounted one end of a slotted finger 27, shown in detail in Fig. 3, the slot in the end of said finger being curved and formed with an internal shoulder 28. In the drawings, a pin or roller 29 is illustrated as extending transversely of the slot in said reed base and riding in the curved slot of said finger. It will be understood, of course, that there are as many slotted fingers as there are reeds, and these fingers are carried by a transverse oscillating bar 30 operated by a short crank arm 31 carried at one end and connected by the vertically-operating rod 32 with the long arm 33 of a bell crank lever, pivotally supported at the base of the machine, and the short arm 34 of this bell crank lever being connected by a connecting rod 35 with an operating lever 36 pivotally mounted at its base, as at 37, and the upper end of which cooperates with a cam member 38 controlled by the movement of the loose driving wheel. The batten may be recessed at 31^a to allow of the free movement of the short crank arm. This cam member is preferably of oval shape, as shown, the nose of the cam being disposed in the same line as the crank arm 20 and the normally dead or butt surface, indicated in dotted lines at 39, being diametrically opposed to the nose. Instead of forming a cam with the dead surface 39, however, it may be desirable to extend this surface a farther distance from the center which will form a circular cam face for a purpose hereinafter referred to. This circular cam face is indicated by the dotted lines at 40. It will be understood that while the nose of the cam 39 is shown as disposed in line with the crank arm 20, the nose of said cam may be arranged out of line therewith to regulate the movement of the reed with relation to the batten at the beginning of the forward stroke or as the going parts are leaving the race.

It will be obvious in operation and with the parts in the position shown in Fig. 2, upon a continued movement of the driving wheel in the direction indicated by the arrow, with the lever 36 about to engage the dead surface of the cam between the positions indicated at *a* and *b* that the lever 36 will have receded to its normal forward position, the slotted finger 27 moving rearwardly, as indicated by the dotted arrow, which will shove the reed rearwardly a limited distance, the pin or roller 29 riding down toward the lower end of the slot. As soon as the lever 36 strikes and is riding over the dead portion *a*—*b* of the cam the reed remains stationary relatively to the batten, and the batten and reed move rearwardly until the point *b* on the cam surface is reached, when the connecting parts between the lever 36 and the reed base will tend to move the reed forwardly, but as the batten is still moving rearwardly the reed practically remains stationary with relation to the shuttle race. The batten continuing to move rearwardly projects the forward end of the reed base beyond the batten owing to the sliding connection between the reed base and the guiding blocks. That is to say, as the batten approaches the rear end of its stroke the movement of the reed which normally projects a few inches rearwardly of the batten is retarded and practically stopped when in a position at the rear of the shuttle race. This retardation, of course, is of short duration, and when the extreme position of the nose of the cam 38 is in engagement with the lever 36 (with the crank arm 20 on the rear dead center) upon continued movement the batten starts forward again, but while the cam engages the lever from the center of its nose to the position *c* the reed practically remains stationary and the distance, between the stationary reed and the receding batten, increasing, their is, during this period, caused a substantial dwell, during which dwell the shuttle passes through the shed in front of the reed before the reed starts to move forwardly on its return stroke, which forward movement of the reed will begin when the cam reaches the position *c*. Until the position *d* is reached the reed will continue to move conjointly with the batten, but projecting rearwardly thereof. When the position *d* of the cam is reached, owing to the cam surface 40, the reed starts to move forwardly again independently of the batten, which is still moving forwardly, and when the central portion of the rear end of the cam is reached the slotted arm 27 is disposed substantially in the position shown in Fig. 3, so that the reed is temporarily locked to the batten by the interposition of the shoulder 28 behind the roller 29. At this position the reed is pressed against the last weft thread or shoot and it remains there momentarily until after the batten has started its movement backward. Of course, before the shuttle is moved transversely in the opposite direction, the heddles indicated by dotted lines at 41 are operated to shift the warp threads 42.

As before stated, the invention is not limited to the exact details, and it is obvious that the invention may be applied to any of the regular makes of narrow fabric looms by simply changing the crank arms and batten.

What I claim is:—

1. In a loom, the combination of a batten, driving means therefor, a reed slidably mounted thereon, and means operating said reed with a continuous motion independently of said batten during a substantial portion of the latter's stroke in both directions of movement, substantially as described.
2. In a loom, the combination of a batten, driving means therefor, a cam operated by said driving means, a reed movably mounted on said batten, and means operating said reed by said cam with a continuous motion independently of said batten during a substantial portion of the latter's stroke in both directions of movement and provided with means controlling the movement of said reed during a portion of said batten's stroke, substantially as described.
3. In a loom, the combination of a batten, a reed movably mounted thereon, and means retarding the movement of said reed while said batten is moving and while the shuttle is passing laterally forward of said reed, substantially as described.
4. In a loom, the combination of a batten, an independently movable reed mounted thereon, and means retarding the movement of said reed at one end of said batten's stroke while said batten is moving and while the shuttle is passing laterally forward of said reed and at the other end of said batten's stroke while said reed engages the last weft or shoot of the woven fabric, substantially as described.
5. In a loom, the combination of a batten, driving means therefor, a sliding reed carried thereby, and means operating said reed with a continuous motion independently of said batten during a substantial portion of the latter's stroke in both directions of movement and provided with means substantially locking said movable reed temporarily at one end of said batten's stroke, substantially as described.
6. In a loom, the combination of a batten, driving means therefor, a sliding reed mounted on said batten, a finger pivotally mounted on said batten and engaging said sliding reed, a short crank arm for said pivoted finger, a bell crank lever, a straight lever, connecting rods between said bell crank lever and said straight lever and said short crank arm, and a cam member operated by said driving means engaging said straight lever, substantially as described.
7. In a loom, the combination of a batten, driving means therefor, a reed provided with a horizontal base slidably mounted on said batten, a rock shaft, a finger carried by said rock shaft, a pin and slot connection between said finger and reed base, and means for rocking said shaft during a portion of said batten's travel, substantially as described.
8. In a loom, the combination of a batten, driving means therefor, a reed movably mounted on said batten, a finger pivotally carried by said batten provided with a slot having a locking projection internally thereof, a pin carried by said reed and operating in said slot, and means for locking said finger on its pivot during a portion of said batten's travel, causing said pin to ride in said slot to a position between the locking projection and the outer end thereof, substantially as described.
9. In a loom, the combination of a batten, driving means therefor, a reed base slidably mounted on said batten and provided with a reed member, a rocking finger mounted on said batten and provided with a slot having a locking projection internally thereof, a pin carried by said reed base and operating in said slot, and means for rocking said finger during a portion of said batten's travel causing said pin to ride in said slot to a position between the locking projection and the outer end thereof, substantially as described.
10. The combination of a batten, a reed slidably mounted thereon, driving means for said batten comprising a crank arm and a pitman between said crank arm and batten, oscillatory means engaging said slideable reed, a movable member, connections between said movable member and oscillatory means, and a cam member having a cam surface disposed in line with said crank arm and engaging said movable member, substantially as described.
11. In a loom, the combination of a batten, a shuttle disposed longitudinally in the same direction as the warp threads and operating through the shed sidewise, and an independently movable reed mounted on said batten and provided with controlling means to retard said reed's movement, as the batten moves away from the shuttle race, to create a dwell while the batten is moving and allow said shuttle to pass forward of said reed, substantially as described.
12. The combination of a batten, a reed movable conjointly with and independently of said batten, driving means for said batten comprising a crank arm and a pitman connecting said crank arm and batten, a cam operating with said crank arm and having two cam surfaces disposed substantially in line with said crank arm, a movable member engaged by said cam, and connections between said movable member and said reed, substantially as described.
13. The combination of a batten, a reed movable conjointly with and independently

of said batten, driving means for said batten comprising a crank arm and a pitman connecting said crank arm and batten, a cam coöperating with said crank arm and having two cam surfaces of different radii

10 said movable member and said reed, substantially as described.

In testimony whereof, I affix my signature, in presence of two witnesses.

SOLOMON KENDRICK.
